UNITED STATES PATENT OFFICE.

MATTHEW A. HIGH, OF ANDERSON, INDIANA.

SANITARY WAITER.

Application filed March 10, 1923. Serial No. 624,264.

To all whom it may concern:

Be it known that I, MATTHEW A. HIGH, a citizen of the United States, residing at Anderson, in the county of Madison and 5 State of Indiana, have invented certain new and useful Improvements in Sanitary Waiters, of which the following is a specification.

This invention relates to waiter or server 10 devices for restaurants or public eating places, and has for its object to provide means whereby the requirements of the guests may be executed economically and quickly, and that the food so served is clean 15 and sanitary.

My invention may be applied to use in connection with the well known type of restaurant counter, and it contemplates a series of tray decks operable in the manner 20 of trap doors, in the deck or top of the counter, the hinged end of each tray deck being near the front edge of the counter and at a height slightly less than the height of the free end of the tray deck, a track 25 on the tray deck, a main track on the counter deck and adjacent to the tray decks, switch tracks leading from the main track to the tray deck tracks, a discharge deck beneath the counter deck, a discharge track thereon 30 switch tracks from the discharge track and at registration beneath the switch tracks on the counter deck, a switch device at each of the switch tracks on the counter deck, operable to open and close the main track, 35 a roller tray to roll to the front end of each tray deck, each of said roller trays provided with a trip thereon to actuate the switch device of the switch track leading to the tray deck to which the roller tray 40 is directed, a latch device to normally retain the tray deck at the raised or closed position, a conveyor means to propel the roller trays on the main track, and on the discharge track, away from the tray decks, means oper- 45 able at the counter deck to retract the latch bar and permit the tray deck to swing, a lifting means to return the tray deck to the raised and closed position, a stool lever at the front of the counter and adjacent to each tray deck, and retained normally at 50 inoperative position, connections between the stool lever and the latch device to hold the latter against movement while the stool lever is at operative position (said opera-

tive position being the position occupied 55 when the guest is seated on the stool) and which said connections so operate that when the stool is released and sprung to the inoperative position, the latch device is operated to release the tray deck, and a means 60 operable to hold the latch device inoperative, when the stool lever may be temporarily released to inoperative position.

By my present invention it is possible for the guest to be waited upon quickly and efficiently, the expense of such service being reduced to a minimum, the guest's order being executed directly by the chef and placed on the roller tray which is thence delivered 65 directly to the guest in prime sanitary condition, and thereafter the used dishes and utensils being delivered on the same roller tray by way of the discharge track to the department of cleansing, in the kitchen, all 70 of the aforesaid operations being performed 75 practically automatically.

In the present specification and drawing, equipment to operate two trays only, is shown. Amplified equipment may be provided to operate an increased number of 80 trays, without affecting the nature of the invention or sacrificing any of its advantages.

The several parts of the invention are identified by suitable characters of reference applied thereto in the different views in the 85 drawings, in which—

Figure 1 is a top plan view of my improved sanitary waiter.

Figure 2 is a front view of Figure 1.

Figure 3 is a vertical transverse sectional 90 view taken on the line 3—3, and as viewed in direction indicated by the arrow 3 in Figure 1.

Figure 4 is a sectional plan view taken on the line 4—4 in Figure 3.

Figure 5 is an enlarged sectional view 95 taken on the transverse line 5—5, and as viewed in direction of the arrow 5 in Figure 1.

Figure 6 is a detached detail view of the 100 means that operates to open and close the main track on the deck of the counter.

Figure 7 is side view of the roller tray.

Figure 8 is a bottom plan view of the 105 roller tray.

Figure 9 is a vertical transverse sectional view of the end portion of the tray, on the line 9—9 in Figure 8.

Figure 10 is a vertical transverse sectional view of the end portion of the tray, on the line 10—10 in Figure 8.

Figure 11 is a vertical sectional view taken on the line 11 in Figure 1.

The structure of the counter may be of usual suitable form, and comprises the paneling 1, and the deck or top 2.

Spaced apart, in the deck of the counter, 10 are platforms adapted to support trays upon which the food for the guest is served. These platforms, and which are designated as tray decks, and are identified by the numerals 3 and 4, may be rectangular in form. 15 They are adapted to operate in a way identical with that of a trap door. The frontal end of each of the tray decks, is hinged to the counter frame, and at a height slightly less than the height at which the free end of 20 the tray deck is retained in a plane or flush with the top surface of the counter deck. The surface plates 5, 6 and 7 besides providing a neat finish for the top surface of the counter, constitute a closure of the sides 25 of the openings for the tray decks, and they also form flanges against which the tray decks reside when at the raised or closed position shown.

Centrally on each of the tray decks is a 30 trackway, consisting of a pair of light metal rails 3^a and 4^a. The tray, which is to be transported from the counter deck to the front portion of the tray deck, is designated as a roller tray, and it consists of a tray 35 proper, mounted on a light frame 8 and in which frame are journaled four flanged wheels 9 that are adapted to roll on the said rails. A metal block 10 secured to the tray frame contributes necessary weight and balance so that the roller tray moves steadily and dependably on the track. At the right hand end of the roller tray and near its rear edge, projects a bifurcated arm 11; and on the underside of the right hand end of the 45 tray near its forward edge is a trip 12 having a projecting portion designated as tongue 12^a. The features and functions of these parts will be presently referred to. For convenience in the description later, of 50 the operation of my invention, I designate the tray that rests on the tray deck 3, as the tray 3^b; and the tray that rests on the tray deck 4, as the tray 4^b. Each of the tray decks is retained at the raised or closed position shown, by a spring-pressed latch bar 55 14. Extending the full length of the counter deck 2, is a main track consisting of the rails 15. From this main track, the switch track rails 3^c and 4^c, lead to the edge of the 60 deck 2 and registration with the rails 3^a and 4^a of the tray decks 3 and 4 respectively. Operable to close and to open the main track is the device illustrated in Figure 6.

The wedge bar 16 which is seated slidingly 65 in engagement with the point of the rail 4^c

has loose connection with lever 17 whose lower end is fulcrumed in a suitable bearing block 18 secured to the frame of the counter. At a short distance ahead of the location of lever 17 is a lever 19 which is fulcrumed on 70 a suitable bearing block. The lever 17 is disposed at an angle slanting rearwardly, and the lever 19 is slanted forwardly. A connecting rod 21 constitutes a loose connection between these levers, so that when the lever 17 is thrown forwardly (see dotted lines) the switch rail 4^c is closed against rail 15, the lever 19 is drawn to rearward position (see dotted lines). Thus when the lever 19 is thrown forwardly (from the dotted line position) the lever 17 is drawn to its original position with the wedge bar 16 retracted, and during which operation, the switch rail 4^c 75 will have been returned to its normal position apart from the main track rails 15 by 80 springs 16^a. The switch operating device for the rails 3^c is similar in all respects to that above described, except that the top of the lever 17 is slightly higher than the lever 17 of the device that operates switch rail 4^c, the 85 reason for which variation will be presently referred to. It will be understood that the counter deck, which is shown as broken away, extends to and has its terminal in the kitchen where the cooking and dispensing 90 of the tray contents, and cleansing operations, are carried on, and that the main track 15 extends to said terminal.

In parallelism with the main track is operated a conveyor of the belt type; this conveyor may consist of a cable which is carried over the grooved pulley 23. At intervals in said cable 24, are lugs 25. Suitable motor driven means (not shown) may be used for operating said conveyor, and which operation is continuous.

The height of the bifurcated arm 11 that projects from the right hand end of the roller tray is such that when the roller tray is placed on the main track 15, the lug 25 100 carried by the conveyor, engages the opening in said arm 11, and the roller tray is propelled at the proper speed toward the tray decks. By reference to Figure 9 it will be observed that the trip 12 has the tongue 12^a. 105 As the roller tray nears the rail 4^c the trip 12 in contact with lever 17 throws it to the dotted line position and the rail 4^c is moved to contact with rail 15; as the roller tray proceeds on the rails 4^c the tongue 12^a throws 110 lever 19 and the rail 4^c is returned to normal position apart from rail 15. Thus the main track is normally open, at the switches, so that the only switch that is closed, as the 115 roller tray proceeds, is the switch whose lever 17 is operable by the tray having trip 12 at the height intended for the same. The switch rails 4^c being returned by the usual 120 spring arrangement 16^a, it is apparent that the roller tray when being transported in the 125 130

direction opposite to that just described, along the switch track, readily enters the main track.

The roller trays are uniform in size and construction except for variation of the depth of the trip 12. This variation is in conformity with the variation of the heights of the switch levers 17. The lever 17 of maximum height is for the switch track 3^e 10 which is at the extreme end of the main track, each lever at location to the right of the left terminal end of the main track, being of decreased height. By this arrangement, the tray 3^b intended for the tray deck 3 passes 15 the switch at 4^e but it actuates the switch operating means at switch track 3^e. Similarly the tray intended for the tray deck 4 actuates the switch operating means at track 4^e.

Journalized in a block that is secured to 20 the underside of counter deck 2 (see Figure 5) is a bell crank having the arms 27 and 28; leaf spring 29 urges arm 27 to raised position, and to which arm 27 is loosely connected a vertical rod having its head of the 25 form of a push button 30, and which occupies a position in the counter deck, conveniently within reach of the guest.

The latch bar 14 is retained slidingly in bearing blocks 31 and 31 arranged on the 30 underside of the counter deck, and is urged normally to the projected position (supporting the end of the tray deck, (see Figure 5) by a spring 32. By means of a rod 33 which has its forward end journaled in bell crank 35 arm 28, and its other end supported slidingly in the bearing block 34, and connected loosely to a pivoted bar 35; the pressure applied at push button 30, is operative to retract the said latch bar 14. The extreme 40 forward end 33^a of arm 33 occupies position in a recess 34 in the frame of the counter, being loosely supported in a guide-way block 35'.

At the front edge of the counter and at 45 location near to that of the roller tray when the latter is at the delivered position (see Figure 3), is a guard plate 37, as shown in Figure 5 and Figure 11. The function of this guard plate is to normally retain or 50 hold certain mechanical parts against action, but which guard plate when raised, will permit said parts to operate. This guard plate is connected to the main structure of the counter, by spring hinges that 55 hold the guard plate at the normal lowered or horizontal position shown, and it normally exerts a pressure against push rod 37^a and bar 38 and which pressure holds said bar 38 at a position apart from the end 60 of the bar 33^a. When the guard plate 37 may be raised the action of spring 39 is to move the bar 38 into position in line with the bar 33^a locking the latter against movement. The purpose of this feature will be 65 hereinafter referred to.

At a position in alignment afront each of the tray decks, is a stool 40, the lower portion of which consists of a lever that is fulcrumed on a bearing block 41. By means of a spring 42 which operates through a bar 70 43 that engages the end of the lever, the stool is held normally at inoperative or unused position and against the front of the counter, as shown in Figure 5.

A bell crank journaled in a bearing block 75 44 has its arm 45 held by a spring 45^a at bearing engagement with the stool lever 46 and its other end is provided with a wrist 47.

The relative positions of the several parts, 80 affecting the operation of the tray decks, are as shown clearly in Figure 5. When the stool 40 is swung to the dotted line position as shown in Figure 3, and upon which stool the guest is seated; the bell crank 85 wrist 47 will have moved to the dotted line position and into engagement with the dog 48. Dog 48 has such connection with the bar 49 whose upper end engages the end of bell crank 27, that a downward pull of the dog and its bar 49, has the same effect 90 on the latch bar, as does the pressure which is exerted at the push button 30.

The bar 49 is supported normally at raised position by a spring 50. Slot 49^a 95 provides clearance at the stud bearing 27^a of the bell crank arm 27.

The guest being seated on stool 40, may inspect the bill of fare and will indicate on the usual card provided by the restaurant, the items of refreshment desired to be served to him. After placing such order-card upon the roller tray—say, the tray 3^b—he simply presses the push button 30. By this pressure on said push button the latch bar 14 is retracted. The tray deck instantly drops or swings downwardly and rides on the roller 51 of a beam 52 which is journaled on frame member 53. This beam is so weighted by a weight 54 carried thereby, and which weight is capable of being secured at adjusted position on the beam by set screw 55 that after the roller tray 100 will have passed from the tray deck, the tray deck is lifted by the weighted beam 52 to its normally raised position. Immediately after the tray deck in its lowering movement, has reached the limit of its travel and which is at the line of registration with the surface of the secondary deck 56, the 105 wheels of the roller tray roll directly on the switch curve 57 where the tray is engaged by lug 25 of the conveyor cable, whence it proceeds along the discharge track 58, whose terminal is in the kitchen. As 110 above described, the beam 52 will have lifted the tray deck to the original or raised position where it again becomes latched by the spring actuated latch bar 14.

In the meantime, the roller tray with its order card aboard has been received by the 130

chef department in the kitchen, for execution. This tray 3^b having then been promptly loaded with the items called for by the said order card, is then placed on the main track 15. The arm 11 of the tray is engaged by the first approaching lug 25 of the conveyor cable 24, and is forthwith hauled on its way as indicated by the arrow 24^a in Figure 1. The trip 12 of the roller tray 3^b passes the lever 17 of switch for the track 4^c, but it makes contact with lever 17 of the switch operating means at track 3^c, and accordingly the roller tray is diverted to track 3^c, and thence it glides at proper momentum down the declined tray deck 3, and comes to a stop at the terminal position at the front of the counter and in position before the guest there seated.

In the event a guest may desire to temporarily remove from the seated position before having completed his repast, he raises the guard plate 37 which permits the bar 38 to rise to a position afront the end of bar 33^a, thereby locking the latter against movement; at the same time the seat 40 remains at the extended or dotted line position. The guest when again seated, returns the guard plate to its original position which depresses bar 38 to its normally lowered position. Upon the departure of the guest from his seated position after having completed his repast, the seat 40 by the action of spring 45^a is drawn and retained at the retracted and normal position as shown in Figure 5. With the consequent lowering of the wrist 47 and the moving of bar 33, the latch bar 14 is retracted. With the consequent release and dropping of the tray deck (see Figure 3) the roller tray, with its load of used dishes and utensils, coasts to the deck switch curve track 57 and the track 58 whence it is engaged by the moving conveyor cable and transported to the kitchen where it is received for unloading to the cleansing department.

As the dog 48^a contacts with trip 60, the dog is disengaged and bar 49 is permitted to return to its normally raised position, the invention being then, in its entirety, in readiness for another operation. While I have described the use of one only, of the roller trays, it is apparent that there may be installed any number of the tray decks and trays with the operating devices incident thereto; each tray being capable of use independently of the others, the studs 25 on the conveyor cable being spaced accordingly. The starting terminal of the main track, and the return terminal of the discharge track, may be disposed, so that the loading of the trays for transport to the guest, and also the receiving of the tray containing the used dishes, at the cleansing department of the kitchen, may be facilitated to the maximum degree.

It will be further understood, that in this description of my invention, I have shown the form of details considered practicable for carrying the invention into effect; it being obvious that refinements, simplification and improvement thereof within the range of equivalents, may be made, without affecting the nature or the principles of the invention.

What I claim as new and desire to secure by Letters Patent is:—

1. A platform main deck, a lower deck, a trap door tray deck which when released has its free end meeting the lower deck, retainer means to hold the trap door normally at raised or closed position, devices to actuate the retainer means to release the trap door tray deck, a roller tray on the tray deck to move to the lower deck when the former is released.

2. A platform main deck, a lower deck, a trap door tray deck which when released has its free end registering with the lower deck, retainer means to hold the trap door tray deck normally at raised position, devices to actuate the retainer means to release the trap door tray deck, a roller tray adapted to roll from the main deck to position on the tray deck, and to roll on the tray deck to the lower deck when the former is released, and means to return the tray deck to the raised position after the roller tray has passed therefrom.

3. A platform main deck, a lower deck, a trap door tray deck which when released has its free end registering with the lower deck, retainer means to hold the trap door tray deck normally at raised position, devices to actuate the retainer means to release the tray deck, a roller tray adapted to roll from the main deck to position on the tray deck, and to roll from the tray deck when the latter is released, means to return the tray deck to normal raised position after the roller tray has passed therefrom, a conveyor means to propel the roller tray on the main deck toward the tray deck, and operating on the lower deck to propel the roller tray in the opposite direction, and means to divert the roller tray from the conveyor to the tray deck, substantially as described.

4. A restaurant service device, comprising a platform main deck, a lower deck, a trap door tray deck which when released has its free end registering with the lower deck, retainer means to hold the tray deck normally at raised position, a device operable on the main deck to actuate the retainer means to release the tray deck, a seat device supported near the tray deck, and retained normally at an inoperative or unused position, connections carried by the seat device to engage the tray deck retainer means when the seat device is moved to operative position, and which said connections actuate the devices that release the tray deck

retainer means when the seat device becomes unoccupied and returns to its normal inoperative position, a roller tray adapted to roll from the main deck to position on the tray deck, and to roll from the tray deck when the latter is released, means to return the tray deck to the normally raised position, a conveyor means to propel the roller tray on the main deck toward the tray deck, and to propel the roller tray on the lower deck away from the tray deck, and means to divert the roller tray from the said conveyor to the tray deck.

5. In a device of the kind described, in combination with a tray deck, and retainer means to hold the tray deck normally at raised position, of a seat device supported near the tray deck and retained normally at an inoperative or unused position, connections carried by the seat device to engage the tray deck retainer means when the seat device is moved to operative position, and which said connections actuate the devices that release the tray deck retainer means 25 when the seat device becomes unoccupied and returns to its normal inoperative position, and a device operable from the main deck to render the tray deck retainer means incapable of being actuated while the seat 30 device is at the operative position.

6. A service device, comprising a platform main deck, a lower deck, a track on the main deck, a track on the lower deck, a trap door tray deck which when released has its free 35 end to register with the lower deck, retainer means to hold the tray deck normally at raised position, a device operable on the main deck to actuate the retainer means to release the tray deck, a seat device supported 40 near the tray deck and retained normally at an inoperative or unused position, connections carried by the seat device to engage the tray deck retainer means when the seat device is moved to operative position, and 45 which said connections actuate the devices that release the tray deck retainer means when the seat device becomes unoccupied and returns to its normal inoperative position, a track on the tray deck, a switch from 50 the main track to the tray deck track, a switch leading from the edge of the lower deck to the track thereon, a roller tray for said tray deck, a conveyor means operable adjacent the main track and the lower deck 55 track, connections on the roller tray to be engaged by the said conveyor, means to operate the switch at the main track, a trip on the roller tray to actuate said switch operating means, means to return the tray deck 60 to the raised position after the roller tray has passed therefrom to the lower deck track.

7. A sanitary service device for restaurants, comprising a platform main deck, a series of trap door tray decks, a track on the

tray deck, a track on the main deck, switch tracks leading from the main track to the tray deck tracks, a lower deck, a track thereon, switch tracks to the lower deck track and at registration beneath switches of the main track, a switch device at each of the switch tracks on the main deck operable to open and close the main track, a roller tray to pass to the front end of each tray deck, a conveyor means to propel the trays in direction toward the switches, an arm on the tray capable of being engaged by the conveyor and of being disengaged from the conveyor as the tray leaves the main track, a trip device on the tray to actuate the switch to divert the tray from the main track, a trip device on the tray to actuate the switch to close the main track after the tray has passed, a latch device to normally retain the tray deck at the raised position, means operable to retract the latch device to release the tray deck, a lifting means to return the tray deck to raised position, a seat device adjacent to the tray deck and retained normally at inoperative position, connections between the seat device and the latch device to hold the latter inoperative when the seat device is at operative position (said operative position being that when the seat is occupied) and which connections cause the latch device to operate to release the tray deck when the seat is unoccupied, and a means operable to hold the latch device inoperative when the seat device is unoccupied.

8. In a device of the kind described, a main deck, a main track, a lower deck, a lower track, a tray deck, a roller tray adapted to roll therefrom, a conveyor to propel the roller tray toward the tray deck, a conveyor to propel the tray away from the tray deck, means to divert the roller tray as it leaves the tray deck, to the conveyor, and means to divert the tray to the tray deck, as it leaves the conveyor.

9. In a device of the kind described, a main deck, a lower deck, a tray deck, a roller tray adapted to roll therefrom, a conveyor to propel the tray toward the tray deck, and to propel the tray in direction away from the tray deck, means to divert the tray from the tray deck to the conveyor, and means to divert the tray from the conveyor to the tray deck.

10. In a device of the kind described, a main deck, a lower deck, a tray deck operable to decline to the lower deck, a roller tray adapted to roll from the tray deck, means to convey the tray away from the tray deck, and means to convey the tray to the tray deck.

11. In a device of the kind described, the combination of a main deck, a tray deck capable of being raised and lowered, a track leading to the tray deck, a lower deck at

whose edge the tray deck registers when at lowered position, a track leading to the edge of the lower deck, a roller tray to roll onto the tray deck from the main deck, and 5 to roll from the tray deck on to the lower deck, means to retain the tray deck at normally raised position, means to release the said retainer means to lower the tray deck, and a device to return the tray deck to the 10 raised position.

12. A device of the kind described, comprising a main deck, a second deck, a tray deck disposed at level with the main deck, a means to retain the tray deck normally at 15 level with the main deck, means to release said retaining means, a track on the main deck leading to the tray deck, a track on the second deck leading from the tray deck, means to shift the tray from the level of 20 the main deck to the level of the second deck, a roller tray adapted to be rolled from the main track to the tray deck, and from the tray deck to the second deck.

13. In a sanitary service device, the combination of a platform deck, a track on the platform deck, a tray deck, a track on the tray deck, a switch track leading from the platform deck track to the tray deck track, a switch device operable to open and close 25 the switch track, a roller tray, a conveyor means to propel the tray in direction toward the switch, an arm on the tray capable 30 of being engaged by the conveyor and of being disengaged from the conveyor as the

tray leaves the platform deck track, a trip 35 device on the tray to actuate the switch to divert the tray from the platform deck track and to actuate the switch to close the platform deck track after the tray has passed. 40

14. In a sanitary service device, the combination of a main deck, a track on the main deck, a second deck, a tray deck disposed at substantially the same level as that of the main deck and capable of being swung 45 apart from and into engagement with the said main deck, a track on the tray deck, a switch track leading from the main deck track to the tray deck track, a switch device operable to open and close the main track, a 50 roller tray to pass from the main deck and on to the tray deck and to be discharged from said tray deck when the latter is swung from its normal position of registration with the main deck, a conveyor to propel the tray on the main deck track in direction toward the switch, an arm on the tray capable of being engaged by the conveyor and of being disengaged therefrom as the tray leaves the main deck track, a trip 55 device on the tray to actuate the switch to divert the tray from the main deck track and to close the main track after the tray has passed, and a track on the second deck 60 to receive the tray when it is discharged 65 from the tray deck.

In testimony whereof I affix my signature.
MATTHEW A. HIGH.
